(57) **CLAIM**

The ornamental design for a hand controller apparatus for a medical device, as shown and described.

DESCRIPTION

FIG. 1 is a perspective view of a hand controller apparatus for a medical device.

FIG. 2 is a front view of the hand controller apparatus of FIG. 1.

FIG. 3 is a rear view of the hand controller apparatus of FIG. 1.

FIG. 4 is a left side view of the hand controller apparatus of FIG. 1.

FIG. 5 is a right side view of the hand controller apparatus of FIG. 1.

FIG. 6 is a top plan view of the hand controller apparatus of FIG. 1; and,

FIG. 7 is a bottom plan view of the hand controller apparatus of FIG. 1.

The broken lines depict portions of the hand controller apparatus for a medical device that form no part of the claimed design.
